[57] CLAIM

The ornamental design for a pendant or similar article, substantially as shown and described.

DESCRIPTION

FIG. 1 is a side elevational view of a pendant or similar article showing my new design, the side opposite being
the same;

FIG. 2 is a side elevational view thereof, as seen from the left hand portion of FIG. 1, the side opposite being
the same;

FIG. 3 is a top plan view thereof; and

FIG. 4 is a bottom plan view thereof.
